UNITED STATES PATENT OFFICE

HENRY K. MULFORD, OF PHILADELPHIA, PENNSYLVANIA, ASSIGNOR TO NATIONAL DRUG CO., OF PHILADELPHIA, PENNSYLVANIA, A CORPORATION OF PENNSYLVANIA

ADAPTER NEEDLE

Application filed May 12, 1927. Serial No. 190,685.

My invention relates to a new and useful needle adapter and more particularly to an adapter needle for a hypodermic syringe of the type employed in administering subcutaneous, intramuscular, or intravenous injections, as well as for use on collapsible tubes.

My invention more particularly relates to a novel needle adapter for syringes and collapsible tubes of the character, whereby needles of different sizes may be employed interchangeably and whereby a broken, damaged, clogged or contaminated needle can be removed and replaced by a new one instantaneously so that no time is lost in cases of emergency.

One object of my invention is to provide a novel adapter which may be operatively connected with or inserted into the interior of a syringe or collapsible tube near the ejection end thereof, instantaneously and in a liquid tight manner, and to which, in turn, any size needle may be coupled or secured also instantaneously and without any elaborate fastening or securing devices.

A further object of my invention is to facilitate the introduction of the injection fluid from the syringe or collapsible tube through the hollow needle to the point of application and to eliminate the liability of the needle becoming clogged in use.

To the above ends my invention consists of an adapter comprising a body portion, an upwardly or inwardly extending stem for piercing the rubber or other closure on the ejection end of a syringe or for entering the nozzle of collapsible tube, said adapter being frictionally or threadedly retained in position, and a pendant extension adapted to fit into a corresponding seat in the upper end of a needle, there being a passage extending through said adapter and forming a communication from the interior of the syringe, to said hollow needle, the passage in said adapter being much larger than the passage in said needle.

My invention further consists of an adapter of this general character having an upwardly extending annular flange adapted snugly to engage the rubber closure on the ejection end of the syringe.

For the purpose of illustrating my invention, I have shown in the accompanying drawings, forms thereof which are at present preferred by me since they will give in practice, satisfactory and reliable results, although it is to be understood that the various instrumentalities of which my invention consists can be variously arranged and organized and that my invention is not limited to the precise arrangement and organization of these instrumentalities as herein shown and described.

In the accompanying drawings, in which like reference characters indicate like parts, Fig. 1 represents a longitudinal sectional view of an adapter needle and its adjuncts and a hypodermic syringe to which the same is applicable, certain parts being shown in elevation.

Fig. 2 represents on an enlarged scale an adapter needle and its adjuncts in detached position.

Fig. 3 represents a longitudinal section view of another embodiment of my invention, Fig. 4 represents a detail view and Figs. 5 and 6 represent a modified construction.

In carrying out my invention, I construct the outlet end of the barrel or cylinder 1 of the hypodermic syringe with a narrowed or constricted mouth as indicated at 2, whereby there is formed an annular wall 3 provided with a terminal bead 4, which is enclosed and tightly engaged by the rubber cap 5 having a rearwardly extending flange 6, which encloses the bead 4 and tightly and snugly engages the wall 3. The adapter needle 7 is composed of the members 8 and 9, the member 8 comprising the head or body portion 10, having a conical, pendant extension 11 and the oppositely extending needle portion 12, there being a passage 13 through said needle portion, body and conical extension 11. The member 9 is provided with an upper head 12^x, having a conical seat 13^x therein, whose contour conforms with the outer contour of the conical pendant portion 11, so that the latter is frictionally and tightly held within the seat 13^x when the members are assembled. 14 designates the needle, which is integral with the head 12 and provided with a passage 15 there-

through, which passage is considerably smaller than the passage 13 in the member 8. In the construction seen in Fig. 3, the needle member 9 is composed of the same elements as already described, comprising the head 12 having a conical seat 13* and the needle proper 14 having the relatively small or restricted passage 15 therethrough. The head 16 is provided with the conical pendant portion 11 already described, but differs from the construction seen in Figs. 1 and 2 by the addition of the annular upwardly extending flange 17 which is adapted tightly and frictionally to engage the rubber cap 5 already described as will be understood from Fig. 3. The hypodermic syringe contains the serum or solution 21 and is provided with a piston or plunger 18 of the usual construction, which is actuated by the piston rod 19 which passes through the closure 20, these parts being of the usual construction. The needle and adapter members 9 and 8 are made of steel or the like and the cap 5 of rubber or similar material.

By the provision of a substantial and rigid adapter member having the upper pointed stem 12, the piercing of the rubber cap or closure 5 at the ejection end of the syringe is easily and quickly effected and the risk of breakage of the needle is eliminated. The relatively large passage 13 in the stem 12 facilitates the passage or flow of the fluid 12 from the cylinder into the relatively restricted passage 15 in the needle 14, and this is especially true when a rather dense or viscous fluid, such as serum or vaccine is being injected, since capillary attraction as well as mechanical friction would otherwise tend to retard the free flow of the fluid to its destination. Especial attention is called to the employment of the relatively large passage 13 in the member 8, since by this construction an elongated relatively large auxiliary reservoir for the fluid or serum is provided, which in practice enables my novel adapter needle to be readily and instantaneously operative under all conditions of use, which is not always the case when the passages 13 and 15 are of the same restricted area in cross section. It is desirable in emergency cases, where sometimes a patient's life is dependent upon the needle functioning instantaneously and positively under all conditions that the needle be instantly operative or capable of instantly performing its desired function, and I have found from practical use of my device that it is essential to have the elongated passage or auxiliary reservoir 13 relatively large as compared to the restricted passage 15 particularly when a rather dense or viscous fluid, as above explained, is to be handled or injected. My novel construction of the adapter member 8 serves to permit of the employment of any size needle, since the extension 11 thereof as well as the coacting seat 13 can be made of

one standard size regardless of the size of the syringe or needle. Furthermore, if the needle is clogged or during injection, the needle should break or be otherwise damaged, it is merely necessary to remove the needle member 9 as a unit and replace the same with any standard slip, or screw hypodermic needle, all of which can be done in a very little time and with a minimum effort.

It is also easy for the operator to use any special standard Luer type slip or screw thread needle, if he desires to use a special size or shape needle for intravenous, intramuscular, subcutaneous and intracutaneous injections.

It is within the scope of my invention to provide an adapter needle particularly suited for use on collapsible tubes and the like, comprising a body portion having a stem projecting therefrom, an internally threaded annular flange surrounding said stem and adapted to engage the threaded outlet of a conventional collapsible tube, and a pendant threaded extension adapted to engage a correspondingly threaded cup shaped seat on one end of a needle, said stem, extension, and needle having aligning passages therethrough communicating with the interior of said tube.

Thus, in Fig. 5 I have shown my novel construction of adapter needle applied to a conventional collapsible tube 22, containing the solution or other fluid 23 and having the usual externally threaded nozzle or outlet member 24. To the nozzle 24 is screwed the adapter member 25 having the body portion 26, the upwardly extending, annular, internally threaded flange 28 and the pendant externally threaded extension 27 which is engaged by the internally threaded cup-shaped head 29 on one end of a needle 14, the passage 30 in said adapter 25 being in alignment with and much larger than the passage 15 in said needle. 31 designates an upwardly projecting stem adapted to project into or enter the nozzle 24 of the tube 22, while 32 designates a gasket of rubber or other material disposed around the base of said stem 31 to prevent any leakage of the contents of said tube, said gasket being compressed between the nozzle 24 and the seat in the adapter 25, when the parts are assembled as seen in Fig. 5.

It will also be apparent that I have devised a novel and useful adapter needle construction which is inexpensive to produce and easy to assemble since the same comprises but two parts and is adapted for a variety of uses.

It will now be apparent that I have devised a novel and useful construction of adapter needle which embodies the features of advantage enumerated as desirable in the statement of the invention and the above description and while I have in the present instance shown and described the preferred em-

bodiment thereof which has been found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters

10 Patent is:

1. An adapter needle for a hypodermic syringe, comprising a body portion having a pointed stem adapted to be retained within the syringe cylinder, an annular flange surrounding said stem and adapted frictionally to engage the closure on the ejection end of said cylinder, and an oppositely disposed conical pendant extension, and a needle having a conical seat on one end thereof adapted 20 to receive said extension, said body and needle portions having aligning passages of different diameters therein communicating with said cylinder, the passage through said body portion being of greater diameter than the passage through said needle.

2. In a device of the character stated, a syringe body having a contracted neck and exit mouth the latter being provided with a terminal annular outwardly flaring bead, 30 a resilient closure engaging said bead and extending around the neck of said exit mouth, a cup shaped member having an outer annular flange and an upwardly projecting, pointed stem and an oppositely disposed 35 pendant conical extension, there being a passage through said stem and extension, and a needle member having a conical seat and provided with a passage therethrough of a lesser diameter than said first mentioned passage, 40 said annular flange frictionally engaging said resilient closure around said bead.

3. An adapter for serum and vaccine syringes of the type having a rubber closure, comprising a body portion having a smooth hollow pointed needle adapted to pierce the closure, said adapter being held in place in the syringe solely by friction with said rubber closure, said adapter having an oppositely disposed tapering extension for the attachment 45 of a needle, the diameter of the passage in the adapter being relatively much larger than the passage through the needles to be used with the syringe, whereby the tendency to clog the adapter is reduced and cleaning 50 in case of clogging is facilitated.

4. In a device of the character stated, an adapter for serum and vaccine syringes of the type having a rubber closure, comprising a body portion having a smooth, hollow, 60 pointed needle adapted to pierce said closure, said adapter being held in place in the syringe solely by friction with said rubber closure, said adapter having an oppositely disposed tapering extension, in combination with a 65 needle having a conical seat adapted for the

reception of said tapering extension, the diameter of the passage in the adapter being relatively much larger than the passage through said needle, whereby the tendency to clog the adapter is reduced and cleaning in 70 case of clogging is facilitated.

5. The combination of a serum and vaccine syringe, having a rubber closure for the discharge end thereof, an adapter therefor, comprising a body portion having a smooth, hollow, pointed needle adapted to pierce said closure, said adapter being held in place in said syringe solely by friction with said rubber closure, said adapter having an oppositely disposed tapering extension and a 75 needle having a conical seat to receive said extension, the diameter of the passage in said adapter being relatively much larger than the passage through said needle, whereby the tendency to clog is reduced and cleaning in 80 case of clogging is facilitated.
